Henry A. Mathews
ATTORNEY.

UNITED STATES PATENT OFFICE

JOHN CLARK, OF WALKERTON, INDIANA

RAILWAY-TIE SPACER

Application filed October 17, 1929. Serial No. 400,341.

My invention relates to a device to be used in connection with railway ties, for spacing the same.

In accordance with my invention, I provide a brace arm having a simple and reliable clamp to secure the brace arm to the rail. When in position, the brace arm will extend generally parallel with the cross tie, and a spacing bar or crow-bar may be fulcrumed 10 against the brace arm to shift the cross tie laterally. The brace arm may be slid longitudinally upon the rail without separation from the same, so that it will remain close to the cross tie being shifted. This will permit 15 of the shifting of the cross tie for any desired distance.

In the accompany drawings, forming a part of this specification, and in which like numerals are employed to designate like 20 parts throughout the same,

Figure 1 is a plan view of a brace arm embodying my invention,

Figure 2 is an end elevation of the same,

Figure 3 is a transverse section taken on 25 line 3—3 of Figure 2.

Figure 4 is a perspective view of the brace arm removed,

Figure 5 is a plan view of a brace arm embodying a modified form of the invention,

30 Figure 6 is a side elevation of the same, and,

Figure 7 is a perspective view of the brace arm removed.

Figure 8 is a section taken on line 8—8 of 35 Figure 6.

In the drawings, wherein for the purpose of illustration, are shown preferred embodiments of my invention, attention being called first to Figures 1 to 4, inclusive, the numeral 40 10 designates a brace arm having an inverted U-shaped socket 11 preferably formed integral therewith. These parts may be advantageously formed of strap iron. The free end of the inverted U-shaped socket 11

45 is bent inwardly to provide a generally horizontal lip 12. The inverted U-shaped socket 11 is adapted to engage over the head 13 of the rail. Particular attention is called to the fact that the inverted U-shaped socket 11 is disposed at an angle with respect to the longi-

tudinal axis of the brace arm 10 and is arranged at an angle of about forty-five degrees with respect to the brace arm and with respect to the longitudinal axis of the head 13 of the rail. The brace arm 10, when in use, is disposed generally parallel with the cross tie. When the device is swung upon the rail head 13 so that the inverted U-shaped socket 11 is arranged at a right angle to the longitudinal axis of the head 13, the lip 12 will be shifted outwardly beyond the head 13 and will clear the head 13 when it is swung upwardly in disengaging the socket from the head 13. A lug 14 is secured to the opposite side of the socket 11 and is adapted to be arranged beneath the head 13 and carries an adjustable bolt 15, to engage with the bottom of the head 13, as shown.

When the device is applied to the head 13 of the rail, the lip 12 and lug 14 are disposed beneath this head, and undue play may be taken up by adjusting the bolt 15. It is not desired that the bolt 15 be brought into clamping engagement with the head 13, as it would prevent the socket 11 being adjusted 55 longitudinally upon the rail head. With the brace arm 10 in position, a spacing bar 16 may be placed in engagement with the edge of the brace arm and the cross tie, as shown in Figure 2, and this shifting bar is fulcrumed 60 upon the brace arm 10. As the cross tie is shifted from the brace arm, the brace arm may be advanced toward the tie by sliding the socket 11 upon the head 13. The pressure of the shifting bar against the brace 65 arm 10, during the use of the shifting bar, serves to clamp the socket tightly upon the rail head 13, preventing slipping in a direction away from the cross tie being shifted. However, the brace arm 10 may be swung toward the cross tie being shifted to longitudinally adjust the device or to remove the 70 socket 11.

In Figures 5 to 7, inclusive, I have shown a brace arm adapted to be secured to the base flange of the rail. This brace arm is designated by the numeral 16', and has a transverse bar 17 rigidly secured thereto, and adapted to be engaged by the shifting bar 18. The brace arm is provided at its outer 75 80 85 90 95 100

end with a transverse loop-handle 19. Formed integral with the inner end of the brace arm 16' is a generally U-shaped socket 20 adapted to receive the base flange 21 of the rail. This U-shaped socket embodies sides 22 and 23 and the side 23 is provided with an inwardly bent lip 24. The socket 20 is angularly disposed with respect to the brace arm 16' and is arranged at an angle of about forty-five degrees with relation thereto, and at a similar angle with relation to the longitudinal axis of the base flange 21. When it is desired to remove the socket from the base flange 21, it is shifted to a position at a right angle to the longitudinal axis of the base flange 21, and the lip 24 will then clear this base flange. A lug 25 is rigidly secured to the side 22 and has a screw-threaded opening to receive an adjusting bolt 26 to engage with the base flange 21, the lug 25 fitting over the base flange. The bolt 26 is provided to take up undue play but it is not desired to have this bolt screwed up sufficiently tight to clamp the socket 20 to the base flange, as the socket should be freed to be slid longitudinally of the base flange 21 toward the cross tie being shifted, so that it will remain suitably close to the cross tie. The shifting bar 18 is fulcrumed upon the end of the transverse bar 17 and pressure from the same will serve to securely clamp the socket 20 to the flange 21, so that the brace arm will not slip upon the rail. The brace arm 16' is shifted or swung toward the cross tie being shifted to loosen the engagement between the socket and base flange 21, or to remove the socket from the base flange.

It is to be understood that the forms of my invention, herewith shown and described, are to be taken as preferred examples of the same, and that various changes in the shape, size and arrangement of parts, may be resorted to without departing from the spirit of my invention, or the scope of the subjoined claims.

Having thus described my invention, I claim:—

1. A device for use in connection with spacing cross ties, comprising a brace arm, and a generally U-shaped socket carried by the brace arm and angularly disposed with relation thereto, said U-shaped socket being adapted to engage over a portion of the rail and be disposed at an inclination to the longitudinal axis of the rail when it has clamping engagement therewith.

2. A device to be used in connection with spacing cross ties, comprising a base arm and a generally U-shaped socket carried by the brace arm and disposed at an inclination with respect to the longitudinal axis of the brace arm and also with respect to the longitudinal axis of the rail when said socket engages over a portion of the rail, said socket embodying spaced sides, an inwardly pro-

jecting lip carried by one side and a stop element carried by the other side and arranged opposite the lip.

3. A device to be used in connection with spacing rails, comprising a brace arm and a generally U-shaped socket carried thereby and disposed at an inclination with respect to the longitudinal axis of the brace arm, said socket being adapted to receive the base flange of the rail.

4. A device for use in connection with spacing cross ties, comprising a brace arm, a generally U-shaped socket carried by the brace arm and adapted to engage over a portion of the rail, said socket being provided at one end with an inwardly projecting lip and at its opposite end with a lug, and an adjustable bolt carried by the lug.

In testimony whereof I affix my signature.

JOHN CLARK.
